UNITED STATES PATENT OFFICE.

LEWIS H. WATSON, OF CHICAGO, ILLINOIS.

IRONING-MACHINE.

SPECIFICATION forming part of Letters Patent No. 293,290, dated February 12, 1884.

Application filed June 25, 1883. (No model.)

To all whom it may concern:

Be it known that I, LEWIS H. WATSON, a citizen of the United States, residing in Chicago, county of Cook, and State of Illinois, have 5 invented certain new and useful Improvements in Ironing-Machines, of which the following is a specification.

This invention relates to a machine for ironing or polishing cuffs, collars, and the bosoms 10 of shirts, and has for its general object to construct a machine that shall iron the bosom of a shirt one way only, whereby the bosom can be ironed out smooth and without wrinkling.

A further object is to construct an ironing 15 or polishing machine with a reciprocating ironing-table which, during its forward reciprocation, shall be mechanically maintained in contact with a rotary ironing-roller, and which, during its return movement, shall be maintained free from contact with the roller, whereby the ironing will be effected but one way.

Among the further objects of my invention are to provide means, under the control of the operator, for raising the table, and devices for 25 automatically operating so as to allow the table to drop at the end of its forward reciprocation; also, to regulate the pressure of the table against the ironing or polishing roller; also, to provide improved means for holding 30 and stretching the bosom of a shirt upon an ironing-table; to prevent shock at the termination of the return movement of the reciprocating ironing-table; to prevent the shirt from becoming soiled while being ironed; and 35 to provide certain improved features of construction and combination, hereinafter described and claimed, and illustrated in the annexed drawings, in which—

Figure 1 is a perspective view of an ironing 40 and polishing machine constructed in accordance with my invention, a portion of one of the guards being broken away and a cloth being shown stretched upon the table. Fig. 2 is a top plan view of the same, with the rotary 45 ironing-roller, the belt-wheel, and a portion of the boxes at the top of the machine removed, the cloth in this instance being omitted from the table. Fig. 3 is a longitudinal section taken on a vertical plane through the machine. Fig. 4 is a detail perspective, showing a portion 50 of the track-frame for supporting the

table, and also illustrating a slide and its adjuncts for operating the clamping and stretching devices. Fig. 5 is a part elevation and vertical section through the devices employed 55 for raising the ironing-table. Fig. 6 is a detail illustrating means for raising the propelling-wheel for the table, which latter is shown in dotted lines. Fig. 7 is a plan view of the under side of the table-top and the shirt holding and 60 stretching devices. Fig. 8 is an enlarged detail, showing in side elevation the jaws for holding the tail portion of a shirt. This view also includes an enlarged representation of an elastic pad to be held between the jaws. Fig. 9 is a 65 top view of Fig. 8. Fig. 10 is a perspective view of the spools and cords attached thereto. Fig. 11 is a section through the same, said figure also including one of the terminals of the cords. Fig. 12 is a detail section taken on a 70 vertical plane through the neck-clamp and a portion of the table, with a pad and cloth thereon.

The stationary frame of this machine consists, essentially, of a pair of vertical sides, A, 75 connected together by hollow end rods, A', and provided at their tops with suitable boxes, a, for the journals of a rotary ironing and polishing roller. This roller B is made hollow, and 80 heated by gas-flame or otherwise, and is driven by means of power applied to the belt-wheel b, fixed upon an extension of one of the roller-journals.

The reciprocating ironing-table, which is arranged to travel under the rotary ironing- 85 roller, is preferably constructed and supported in the same manner as the ironing-table embraced in an application for Letters Patent heretofore filed by me in the United States Patent Office—that is to say, it is made of 90 metal, and composed of a flat top, C, Figs. 2 and 12, supported upon a base or carriage portion, C', by means of an intermediate neck or middle supporting-piece, C², which latter is recessed or cut away at one end, so as to admit 95 of a shirt being slipped on the table-top. This latter portion of the table is also provided with a marginal line of hooks for holding down the layer or layers of cloth that will be stretched upon the top. The base or carriage portion 100 of the table is supported upon a track-frame, D, provided with longitudinal grooves d, that

correspond and register with like grooves, c , in the base portion of the table, whereby loose anti-friction wheels or rollers can be arranged in said grooves and the table be supported by and adapted to run upon such wheels or rollers. These rollers are free to travel along the grooved track-frame, and are prevented from running off therefrom by means of appropriate stops, c' , arranged in the grooves of both the track-frame and in the base portion of the table.

As a means for raising the ironing-table so as to bring and hold it up against the ironing-roller during its forward reciprocation, I provide a treadle and mechanism intermediate of the treadle and the track-frame, upon which latter the table is supported, whereby by actuating the treadle the track-frame and table can be lifted.

20. E denotes the treadle, fulcrumed in a small casting or other suitable support, e , that can be conveniently arranged upon the floor at the front of the machine. This treadle is connected by a link, E', with a weighted bell-crank lever, E'', that is fixed upon a rock-shaft at the front side of the machine. Between this bell-crank and the track-frame that supports the table is arranged a vertical shaft, E³, provided with a hand-wheel, and having in its lower end a screw-threaded socket, e^4 , (see Fig. 5,) in which a screw, e^5 , is received, that is pivotally connected to one of the arms of the bell-crank, and provided with an adjustable jam-nut, e^6 . Within a socket, e^6 , in the upper end of the rod E rests one end of a shorter and smaller vertical rod or pin, e^7 , that passes through an opening in one of the end cross-bars, A', of the stationary frame. The upper portion of this pin passes through an elastic cushion, E⁸, interposed between said bar A' and the track-frame D, and at its top end abuts against a screw, e^9 , in the track-frame. By thus supporting the latter, it will be seen that when the bell-crank is turned, so as to lift the rod and pins that are arranged in line between the bell-crank and the track-frame, said frame will be raised, and hence the table elevated and brought up close to the ironing-roller. By stepping the pin e^7 —that is, between the track-frame and the rod carrying the hand-wheel—in a cup-shaped socket in said rod, the rod, pin, and screw e^9 at the lower end of the rod can all be brought up in line upon the dead-center when the track-frame and table are raised, as in Fig. 5, and hence said members retained in such position until thrown from off the dead-center, which is automatically effected when the table arrives at the end of its forward reciprocation by the following means:

65. A bell-crank lever or rocker, F, (see Figs. 2 and 3, in which latter figure the upper arm of the lever is shown in dotted lines,) is pivoted to one side of the track-frame D at such point that at the completion of the forward reciprocation of the table a knocker, c^3 , therein on the side of the latter will strike the up-

per arm of the bent lever or rocker F. This rocker connects by a rod, f, with an arm, F', secured upon the rock-shaft F², which latter carries the weighted bell-crank E², that, as hereinbefore described, constitutes a part of the mechanism employed for raising the table. When the bell-crank F, pivoted to the track-frame, is struck by the dog or knocker upon the table and turned so as to give a pull upon rod f, the rock-shaft carrying the weighted bell-crank will be turned, and hence the rods or practically jointed rod between the weighted bell-crank and the table-support or track-frame will be broken or thrown off the dead-center, as in Fig. 3, so as to allow the frame, and consequently the table, to drop below the ironing-roller preparatory to the return movement of the table. The elastic cushion E⁴ under the track-frame takes up the shock when the table drops, and the weight E⁵ upon the bell-crank E² serves as a counter-balance for preventing too sudden a drop on the part of the table. The hand-wheel E⁶ upon rod E³ admits of the latter being turned, in order to give it a vertical adjustment upon the screw that is pivoted to the weighted bell-crank, so as to regulate the pressure of the table upon the roller. In order to give the table a forward movement, and also to cause a reversal of such movement simultaneously with its drop at the end of its forward reciprocation, I provide the following means.

Upon a transverse and centrally-located rotary shaft, G, that is mounted in suitable bearings on the sides of the stationary frame, I key a double flanged spool, H, upon which cords or wires h, wound in opposite directions, respectively run, and are attached to the front and rear ends of the base portion of the table, so that reverse revolutions on the part of the spool will cause reciprocations on the part of the table. One end of this shaft is, as best shown in Fig. 6, journaled in a two-part box, G', the lower half of which is capable of vertical adjustment in any ordinary way for the purpose of raising and lowering the shaft. The adjustable bearing or lower half of this box is connected with a lever, g, that is fulcrumed on a bracket, g', pendent from the main frame, and at its lower end connected in any suitable way—as, for example, by a bent rod, g²—with an arm, g³, Fig. 1, upon rock-shaft F², which, as already stated, also carries the mechanism for raising the table or for allowing the same to drop.

The shaft G, that carries the spool, is also provided at the end that is journaled in the adjustable box with a wheel, G², which, when the box is adjusted so as to raise the shaft, is brought to bear against a friction-pulley, B', arranged between the belt-wheel and the ironing-roller and fixed upon the extended journal of the latter. Hence, when the face of the wheel G² is in frictional contact with the friction driving-pulley, the shaft carrying the spool will be rotated, and one of the cords will pull upon one end of the table and wind upon the spool

as rapidly as the table advances, the remaining cord or wire being proportionately unwound from the spool. Power for the return movement of the table is stored up by means of a coiled spring, G^3 , Fig. 2, arranged upon the shaft, so as to wind up as the shaft is rotated to give the table its forward movement, which can be readily effected by attaching one end of the coil to the shaft and securing the remaining end of the coil to a stationary part of the main frame, or to any fixture thereon. By such arrangement the spring comes into action as soon as the shaft G has been lowered sufficiently to remove the wheel thereon from frictional contact with the friction-pulley. After placing a shirt upon the table, which is done by fitting the shirt thereon like a sleeve, means are required for holding and stretching it—the shirt.

The clamp I , for holding down the neck portion of the shirt, consists of a horizontal plate adapted to the shape of the said neck portion, and arranged to fit, when lowered, into a like-shaped seat that will be cut in the cloth and elastic pad, which will be placed upon the table so that the top of the clamp-plate shall be below the top face of the table-pad C^4 and cloth C^5 in Fig. 12. The vertically-movable clamp-plate I is corrugated or serrated upon its under face in order to prevent the shirt from slipping, and is supported upon a vertical rod, I' , which is pivoted or swiveled to the plate. This rod has a pin, i^2 , near its lower end, which said end is arranged both to slide vertically and to turn in the base portion of the table. Between the pin i^2 upon the rod and the under side of the table-top is a spring, i , which, pressing downwardly upon the pin, exerts a constant tendency to draw down the clamp-plate. The neck-clamp is raised against the spring resistance by means of a T -lever, I^2 , Fig. 3, hung upon one side of the lower portion of the table, and provided in its upper arm with a notch, i^3 , in which the pin i^2 upon the vertically-movable rod I' is received, so that when the lever is raised it will lift rod I' . As there will be a tendency on the part of the lever swinging in the arc of a circle to turn the pin around the axis of the rod, the latter is so arranged as to turn, thus allowing a free action of the parts, and hence admit of the clamp-plate being raised, which is, however, prevented from turning by means of a pin, i^4 , fixed to the plate and working in a hole in the table. This lever carries on its lower arm a small wheel or roller, and is swung up by means of an incline, K , upon a slide, K' , arranged to work in or upon suitable ways, k , Fig. 4, that are provided upon the inner sides of the track-frame. This slide is conveniently constructed of an approximately T shape, with its arms resting upon said ways and its slotted stem resting upon a cross-bar, k' , and guided thereon by a nut, k^2 , received in the slotted portion of the slide and bolted upon the cross-bar. The incline K of this slide is arranged to strike the roller carried by the swinging lever I^2 when

the table is back, as in Fig. 3, and the slide thrown forward, whereby the operator can readily place the neck portion of a shirt under the clamp, or remove the shirt after it has been ironed, when the clamp-plate I is in a raised position. The slide thus provided with an incline, K , for raising the neck-clamp, is operated by a rock-shaft, L , carrying an arm, l , that is connected with the slide by means of a connecting-rod, l' . This rock-shaft is supported in suitable bearings below one end of the track-frame or table-support, and is provided with a crank-handle, L' , by which it can be conveniently operated by the person running the machine. The slide K' is also employed as a means for operating a pair of reciprocating jaws of a combined shirt holder and stretcher, employed for holding the tail portion of a shirt and stretching the bosom thereof upon the table after the shirt has been caught at its neck end by the neck-clamp. To such end I provide the slide with a second incline, K^2 , which is adapted to actuate the bell-crank N , connected with the combined holding and stretching devices, and which is also set somewhat back of the incline K , that actuates the neck-clamp, whereby the action of the inclines shall be successive, as will be hereinafter more fully explained. The said holding and stretching mechanism M comprises a pair of jaws, m and m' . The jaw m , which may be termed the "fixed jaw," is loosely mounted upon the outer ends of a pair of horizontal slide-rods, M , parallel with each other, and arranged to pass back under the top C of the ironing-table, from which they are supported by suitable eyes or bearings, m^2 , attached to the table. The movable jaw m' of this pair is fitted to slide upon the rods M , and is spring-seated thereon, it being pressed outwardly and normally held upon the rods at a point near the outer fixed jaw by means of short coils of stout springs, m^3 , arranged on the rods between the movable jaw, and nuts or stops m^4 , that are secured upon the rods. The rods, and consequently the jaws, are thrown forward and held out from the table by means of springs m^5 , Fig. 7, arranged between stops or shoulders m^6 , rigid on the rods, and the bearings m^2 , through which the rear or inner ends of the rods pass, or other suitable stops on the table. The movable jaw has upon the lower portion of its inner face a stop-pin, m^7 , which will, when the jaws are closed, strike the opposite jaw, and thereby cause the upper portion of the jaws to firmly grip the shirt that will be placed between them. These jaws thus mounted upon the rods have a simultaneous reciprocating movement as the rods are thrown outwardly or retracted under the table. The inner spring-jaw, m' , is connected by a connecting-rod, n , (also shown in dotted lines, Fig. 3,) with the upper arm of a bell-crank lever, N , that is pivoted to one side of the table, as in Fig. 1, and in which latter it is shown in dotted lines. The lower arm of this bell-crank lever carries a roller, n' , against which the incline K^2 , Fig.

4, of the slide is designed to act, whereby when said incline strikes the roller the bell-crank lever will be turned, and hence tension exerted upon the inner jaw, m' , through the medium of the connecting-rod.

5 The short springs m^3 —which I term the “gripping-springs”—are much stronger than the springs m^4 for the slide-rods, so that when the connecting-rod n pulls upon the inner 10 jaw springs m^4 will yield, and hence the slide-rods and both jaws will be moved simultaneously until the gripping-springs m^3 are checked by reason of the stops or nuts m^6 coming in contact with the table, after which a continuance of the tension upon the inner jaw will 15 compress the gripping-springs m^3 , and thereby open the jaw, in order to allow a portion of the tail of a shirt to be forced in between the jaws by a suitable pad or piece of some elastic 20 material. As the incline is drawn from under the bell-crank N , however, the reverse of such action will take place—that is to say, the short stout gripping-springs will force the movable jaw forward, so as to cause it to grip the pad 25 and shirt before the long springs m^4 commence to throw the rods outward in order to stretch the bosom of the shirt upon the table. When the table arrives at the end of its return movement, it becomes necessary to provide means for 30 either taking up the shock or stopping the table in such manner that there shall be no liability of injury to the parts. To such end I provide a brake mechanism consisting of a 35 brake-lever, P , having a shoe arranged to be thrown upon the wheel G^2 , which, as already stated, is fixed on the shaft carrying a spool, from which cords or wire run to the ends of 40 the table for the purpose of reciprocating the same. The brake-lever is practically in the nature of an arm upon a rock-shaft, P' , mounted at one end of the machine, and carrying at or about its middle portion a bent arm, P^2 , that can be made in one or two parts, as desired. This arm P^2 is bent so as to lie in the path of 45 the base portion C' of the table, which said base is in the nature of a rectangular frame, and is so arranged that just before the completion of the return movement of the table the forward end, d , of the table-base shall 50 strike and depress said arm P^2 , and thereby turn the rock-shaft and throw the brake-shoe upon wheel G^2 and stop the table. When the table is elevated, preparatory to its forward movement, it will release the brake-arm 55 P^2 , and thereby loosen up the brake.

The spool H is provided with two peripheral flanges, H' , between which the wires or cords are wound; and in order to insure the regular winding up of the latter, and also prevent a cord winding upon itself and slipping off the spool, I form the latter and connect the cords or wires therewith as follows: The inner wall of each flange of the spool is formed vertically to the axis of the shaft and on a 60 plane running spirally thereto, so as to form a shoulder or vertical end, h^2 , in such flange. 65 The cord or wire passes through an opening

in the spool at the base of such end or shoulder, and is prevented from slipping out by means of a knob, h^3 , fitted in a recess, h^4 , communicating with said opening, and formed at one side of the axial bore through the spool. By such construction the cord or wire can be passed from the interior of the spool out through this lateral passage, and drawn outwardly until the knob at its end is received in the recess h^4 . It will be seen by referring to Fig. 10 that when the cord or wire is wound round the spool it will, in following the spiral wall, necessarily lie in a coil form upon the 70 cylindrical portion of the spool.

The table is held down upon the rollers in any suitable way—as, for example, by means of bent finger-bars Q ; and in order to prevent shirts or other articles that are being ironed 75 from coming in contact with the operating devices, and thereby becoming soiled, I secure upon the table guards R , which are preferably made of sheet metal bent into the shape shown, and strengthened by a bar of metal, r , around the outside, said guards being secured to the base portion of the table, and made with an outward flare, whereby they shall extend up alongside of the sides of the table. These 80 guards will be made detachable from the table, so that when desired they can be removed, and access can thereby be had to the operative parts of the machine.

In operating this machine for ironing a shirt, the ironing and polishing roller will be 85 properly heated and the handle L' thrown forward, as in Fig. 4, so as to operate slide K' , and thereby lift the neck-clamp and open the holding and stretching jaws. As the handle is thus thrown forward and slide K' advanced, 90 incline K^2 acts on the bell-crank, which, through the medium of the connecting-rod, pulls upon the spring-seated jaw, and thereby 95 draws the slide-rods and both jaws inwardly until stops m^6 strike the table, after which the gripping-springs m^3 will be then compressed and the movable jaw opened. The incline K then raises the lever I^2 , which lifts the rod, carrying the neck-clamp against the spring-pressure. The operator then slips the shirt 100 upon the table, places the neckband under the neck-clamp, and wedges in between the jaws m and m' a portion of the tail part of the shirt by means of the pad O , which is allowed to remain between the jaws. A back or 105 reverse movement of the lever-handle L' will now draw back the slide, during which operation incline K will clear the lever I^2 before incline K^2 clears the bell-crank above it, since in the previous operation the incline K^2 , after 110 acting upon the bell-crank, passes by the roller thereon to some extent before the incline K acts upon the neck-clamp mechanism. As a result of thus timing the parts, the spring 115 forces down the neck-clamps and holds the shirt at the neck, after which the incline K^2 clears the bell-crank N , whereby the pad and shirt will be firmly gripped between the jaws and the latter thrown out from the table, so as 120 125 130

to effectually stretch the bosom of the shirt thereon. The operator then presses down treadle E, as in Fig. 1, thereby vibrating the weighted bell-crank lever E², and hence, 5 through the medium of devices already described, lifting the table, so as to bring its propelling-wheel G² in frictional contact with the friction driving-pulley B'. The table then moves forward, subjecting the shirt to the action 10 of the rotary ironing-roller. Arriving at the end of its forward movement, the dog or knocker e³ strikes the bell-crank connected with the devices previously employed for raising the table, and by a reverse turn of the 15 rock-shaft F² throws rod E³ off the dead-center and allows the table to drop, as in Fig. 3. The spring G³, which has been wound up during the forward movement of the table, now unwinds and moves the table back, during 20 which motion the shirt will not be acted upon by the ironing-roller, owing to the lower elevation of the table. As the table reaches the end of its return movement it strikes the brake, and thus applies the same to the propelling-wheel, so as to stop the table and prevent shock. 25

In conclusion, it will be observed that, should the table be elevated and started while the slide K' is forward and the neck-clamp up, the clamp-30 plate I will be automatically drawn down before reaching the ironing-roller, since the instant the lever I' leaves the incline K, by which it has been upheld, the spring i will instantly draw down the neck-clamp. Also, when the 35 table is raised, the treadle E will be down, as in Fig. 1, and when the table is lowered said treadle will be up, as in Fig. 3, in position to be depressed by the operator as soon as necessary.

40 It will be obvious that means could be provided for raising and lowering the ironing-roller in lieu of raising and lowering the table—as, for example, the devices now used for raising the table could be employed for raising bearings for the roller-journals.

Having thus described my invention, what I claim, and desire to secure by Letters Patent, is—

1. In an ironing-machine, an iron and an ironing-table, in combination with mechanism, substantially as described, operating to move the table forward in contact with the iron, lower the table at the end of its forward movement, and return the table to the limit 55 of its backward stroke without contact with the iron, substantially as set forth.

2. The combination of an ironing-table with mechanism, substantially as described, operating successively and automatically to move 60 the table forward, lower the table at the end of its forward stroke, and return the table in its lowered position to the limit of its backward stroke, substantially as described.

3. The combination, substantially as herein 65 described, of the iron and ironing-table with mechanism operating to reciprocate the table, an operating mechanism by which the table

is brought up to and held against the iron during its forward stroke, and mechanism connected with and actuated by the table at the 70 end of the forward stroke of the latter, and operating to lower the table-lifting mechanism, whereby the table shall be automatically lowered at the end of each forward stroke and returned in a lowered position, substantially 75 as set forth.

4. In an ironing-machine, the ironing-table provided at one end with a clamp operating to hold down the shirt-bosom at the neck, and at its opposite end provided with an extensible gripping and stretching mechanism, substantially as described, whereby the shirt may be held at the tail portion thereof and outward from one end of the table, in order to stretch the shirt thereon, substantially as de- 85 scribed.

5. An ironing-table provided with means at one end for holding the neck end of the shirt, in combination with a combined shirt holder and stretcher at the opposite end, 90 consisting of a clamp mounted substantially as described, whereby it may be extended out from the end of the table, and comprising a pair of jaws and a spring connected to the inner jaw, next to the table, to force the same 95 against the face of the outer with a yielding spring-pressure, substantially as described.

6. As a means for stretching a shirt upon an ironing-table, the combination, with a table provided with means for holding the shirt 100 at one end, and with supporting-guides, of a pair of slide-rods mounted in said guides, springs connected with said rods, substantially as described, to throw the rods out from the table, and a jaw rigidly connected with 105 said rods, a movable jaw supported upon said rods, and springs of greater strength than the springs employed for projecting the rods connected with the movable jaw, substantially as set forth, and for the purposes specified. 110

7. An ironing-table provided with means for holding the neck end of a shirt, and provided with supporting-guides, in combination with means for stretching the bosom of the shirt upon the table, consisting of a pair of 115 slide-rods mounted in said guides, springs connected with said rods, substantially as described, for projecting the same out from the table, a fixed jaw rigidly connected with said rods, and a sliding jaw and the stops supported on said rods, and springs located between the sliding jaw, the said springs being of greater force than the spring or springs 120 acting on the slide-rods, substantially as described. 125

8. In an ironing-machine, the ironing-roller and the ironing-table provided with a seat in its top face, in combination with a vertically-movable clamping-plate for the neck portion of a shirt, constructed to fit in said seat, and means operating to automatically raise and lower the clamp, substantially as described. 130

9. In an ironing-machine, the combination, with a supporting-frame, a table normally

- mounted thereon, and provided with a clamp-seat recessed in the upper face of said table, a clamping-plate fitted to said seat, a spring connected to said clamping-plate and serving 5 to draw the same into the seat, means for reciprocating the table, and devices, substantially as described, for raising the clamping-plate at the termination of the backward stroke of said table, substantially as described.
10. The combination, in an ironing-machine, of the reciprocating and vertically-movable table, with mechanism operating to propel the table forward, a mechanism, substantially as set forth, by which the table is raised and 15 the forward-propelling mechanism is brought into action, mechanism operating to lower the table at the end of its forward stroke and throw the forward-propelling mechanism out of action, and a spring connected indirectly 20 with the table, substantially as set forth, to cause the return movement of the same, as and for the purposes specified.
11. As a means for causing the forward movement of an ironing-table in an ironing-machine, a friction drive-pulley, a propelling-wheel, and a movable bearing, in combination with mechanism connected with a movable bearing by which the table and propelling-wheel are raised and the latter brought into 25 frictional contact with the friction drive-pulley, and means, substantially as described, connecting the propelling-wheel with the table, whereby when the propelling-wheel is raised the table shall be forced forward, substantially as set forth.
30. 12. The combination, in an ironing-machine, of the reciprocating ironing-table with a rotary friction drive-pulley, a propelling-wheel, G^2 , a movable bearing for the same, and mechanism 35 connected with movable bearing for raising said wheel up to the friction drive-pulley, and means connecting the propelling-wheel with the table, by which the latter is advanced while the propelling-wheel and pulley are in frictional contact, substantially as described.
13. The ironing-table and mechanism for reciprocating the said table, in combination with a rotary spool, two cords or wires wound in reverse directions upon the spool and connected with the table, mechanism, substantially as described, for rotating the spool in opposite directions, and mechanism, substantially as described, for automatically throwing out of action the forward-propelling mechanism of the spool when the table arrives at the end of its forward stroke, as and for the purposes set forth.
14. The combination, in an ironing-machine, of the reciprocating ironing-table with a spool 50 secured upon a rotary shaft, and having cords or wires wound thereon in reverse directions and connected with the table, frictional drive-gear, substantially as described, by which the shaft is rotated in one direction, and a spring 55 attached to the shaft, substantially as set forth, by which the latter is rotated in a reverse direction, substantially as described.
15. In an ironing-machine, the combination of an ironing-table with a clamping-plate for the neck portion of a shirt-bosom, a support 70 for said clamping-plate, extending through and below the table, and a horizontal slide provided with an incline formed and located with relation to the support for the clamp substantially as described, whereby when said incline 75 strikes the clamp-support both the latter and the clamp shall be raised, substantially as and for the purpose set forth.
16. The combination, in an ironing-machine, of the ironing-table, means for reciprocating 80 the same, with the slide K' , provided with an incline, a rock-shaft having a suitable operating-handle, and provided with an arm, l , a link connecting the slide and arm l , and a neck-clamp mechanism, substantially as described, carried by the table, substantially as 85 and for the purposes set forth.
17. The table, neck-clamp mechanism, consisting of a clamp-plate, I , a vertically-movable rod supporting the clamp-plate, a spring connecting the table and rod I' , substantially as 90 described, and a pivoted lever, I^2 , provided with a notch, in which a pin on the rod is received, said members being combined for operation and carried by the ironing-table, substantially as described.
18. The ironing-table and mechanism for actuating the same, and the spring-seated jaws, in combination with an incline and mechanism connecting said jaws with the incline, substantially as and for the purpose set forth.
19. The supporting-frame, the ironing-table and means for actuating said table, and the clamp having a spring-seated jaw, in combination with the slide provided with an incline, 105 the bell-crank, and rod connecting said bell-crank and jaw, substantially as described.
20. The supporting-frame, the ironing-table, and means for reciprocating the same, in combination with the slide-rods M , the fixed and movable jaws on the ends of said rods, the bell-crank pivoted to the table and connected with the movable jaw, and means for actuating said bell-crank and the spring m^3 , substantially as described.
21. The ironing-table, its supporting-frame, and means for reciprocating said table, in combination with the treadle and devices connecting said treadle with the table, and means, substantially as described, connecting the driving mechanism and the treadle-connections, whereby the downward movement of the treadle will raise the table and the table be allowed to drop at the end of its forward movement, as and for the purpose specified.
22. The frame, the table, and means for reciprocating the table, in combination with a treadle, the rock-shaft, the bell-crank fixed on said rock-shaft and connected with the treadle, the shaft E^3 , and the screw supporting said shaft at one end of the frame, substantially as described.
23. The combination, with a reciprocating

ironing-table and a frame supporting the same, of a jointed support for one end of said frame and means for supporting the other end, substantially as set forth, and a treadle connected with the jointed support, substantially as described, whereby the joint may be flexed to lower the frame and have its members brought

on a dead-center, in order to extend the support to its highest limit, as and for the purpose specified.
